UNITED STATES PATENT OFFICE.

BERNARD A. PAYSON, OF TYRCONNELL, ONTARIO, CANADA.

PENCIL-ERASER.

No. 870,990.

Specification of Letters Patent.

Patented Nov. 12, 1907.

Application filed January 12, 1907, Serial No. 852,031.

To all whom it may concern:

Be it known that I, BERNARD A. PAYSON, a subject of the King of Great Britain, residing at Tyrconnell, in the Province of Ontario and Dominion of Canada, have 5 invented new and useful Improvements in Pencil-Erasers, of which the following is a specification.

This invention relates to pencil erasers, and one of the principal objects of the same is to provide means for adjusting the rubber eraser tip at the end of the 10 pencil to compensate for the wear of said tip..

Pencil erasers as usually employed and secured to the end of a pencil are very liable to become detached and lost, and moreover when detached are only replaced with considerable difficulty.

15 It is the purpose of my invention to provide means for securely holding the eraser tip to the pencil, and to permit the tip to be adjusted as it is worn away.

Another object of the invention is to provide simple means for connecting and adjusting the tip.

20 These and other objects may be attained by means of the construction illustrated in the accompanying drawings, in which:

Figure 1 is a side elevation of a pencil provided with my adjustable eraser secured thereto. Fig. 2 is an enlarged vertical sectional view of the upper end of the pencil having my eraser secured thereto. Fig. 3 is a perspective view of the sleeve which I employ for securing the eraser tip in adjusted position. Fig. 4 is a vertical sectional view similar to Fig. 2, and showing a 25 modified construction of holding devices for adjustably securing the eraser tip in the sleeve. Fig. 5 is a detail perspective view of one of the holding devices shown in Fig. 4.

Referring to the drawings for a more particular description of the invention, the numeral 1 designates a pencil which may be of the usual or any preferred form or construction. Fitted to the upper end of the pencil is a sleeve 2, said sleeve having oppositely disposed vertical slots 3, said slots having a plane vertical wall 35 4 and a series of upwardly projecting hooks 5, said hooks projecting in opposite directions within the slots 3, as shown more particularly in Fig. 3. An ordi-

nary rubber pencil eraser is provided with a pin 7 near its lower end, said pin extending through the tip 6 and through the slots 3 in the sleeve 2. As shown in 45 Figs. 4 and 5 in place of the pin 7 oppositely disposed holding devices 8 are provided, said holding devices having oppositely disposed barbs 9 and a head 10 forming finger holds for adjusting the eraser tip 6 within the sleeve 2.

The operation of my invention may be readily understood from the foregoing. Whenever it is required to adjust the tip 6 within the sleeve 2 it may be pulled outward and slightly turned until the ends of the pin 7 or the shank portions of the holders 8 are disposed 50 against the vertical walls 4 of the slots 3. When withdrawn the required distance, a slight turn of the tip 6 will engage the ends of the pin 7 or the shank portion of the holders 8 with a pair of the oppositely disposed hooks 5, as will be understood.

60 From the foregoing it will be obvious that my invention is of simple construction, can be quickly adjusted to compensate for the wear of the eraser tip, will prevent the loss of the tip from the sleeve, and can be applied to pencils of any character.

65 It will be noticed that the pin 7 projects beyond the sleeve 2 at opposite sides thereof to provide finger holds for turning the tip within the sleeve for adjustment. The heads 10 of the pins shown in Figs. 4 and 5 also serve the same purpose.

70 Having thus described the invention; what I claim is:

The herein described pencil eraser comprising a sleeve fitted to the end of a pencil and provided with oppositely disposed longitudinal slots, oppositely disposed upwardly 75 projecting hooks on one side of each of said slots, a rubber eraser tip, means connected to said tip near the inner end thereof and projecting beyond the sleeve to form finger holds for adjusting the tip, and said means engaging the hooks of the sleeve, substantially as described.

80 In testimony whereof, I affix my signature in presence of two witnesses.

BERNARD A. PAYSON.
